UNITED STATES PATENT OFFICE.

MAURICE A. SMITH, OF JEANNETTE, PENNSYLVANIA, ASSIGNOR TO MCKEE GLASS COMPANY, OF JEANNETTE, PENNSYLVANIA, A CORPORATION OF PENNSYLVANIA.

GLASS-ANNEALING FURNACE.

1,342,233.

Specification of Letters Patent.

Patented June 1, 1920.

Application filed May 15, 1919. Serial No. 297,292.

To all whom it may concern:

Be it known that I, MAURICE A. SMITH, a citizen of the United States, and resident of Jeannette, in the county of Westmoreland 5 and State of Pennsylvania, have invented a new and useful Improvement in Glass-Annealing Furnaces; and I do hereby declare the following to be a full, clear, and exact description thereof.

10 My invention relates to a furnace for annealing articles of glass-ware, and relates more particularly to a stationary type of lehr or annealing furnace as distinguished from the type most commonly used, where 15 the glass-ware is deposited at one end of the furnace on an endless conveyer and passes to the other end where it is removed.

15 The object of my invention is to provide an annealing furnace or lehr of this character which is adapted for use with either producer gas or natural gas as a fuel, and at the same time a furnace which is economical in operation, the construction being such that a maximum amount of heat is obtained with a minimum consumption of gas.

20 To these ends my invention comprises the novel features hereinafter set forth and claimed.

25 In the accompanying drawings Figure 1 is a sectional side elevation of my improved furnace, Fig. 2 is a section on the line 2—2 Fig. 1; and Fig. 3 is a section on the line 3—3 of Fig. 1.

30 In the drawings the numeral 2 designates a suitable base or foundation with the excavation or pit 3 for the lower part of the furnace, the floor line being indicated at 4.

35 The side-walls 5 are built up from the bottom of the pit 3 and connected at the top by the roof 6, said side and top walls being built of suitable refractory brick.

40 Vertical flues 7 are formed in the side walls at suitable intervals, said flues communicating at the top where they enter the 45 flue 8 communicating with the stack-flue 9.

45 This stack-flue 9 is provided with a sliding damper-plate 10 for controlling the draft.

50 Arches 11 are thrown across from one side wall to the other, and said arches form the support for the bottom 12 of the annealing chamber 13.

55 Between the arches 11 are the checker-work chambers 14, the outlets through the checker-work communicating with the

cross-flues 15 which in turn communicate with the vertical-flues 7.

Gas-pipes 16 at the front of the furnace have the inwardly extending burners 17 at their lower ends which project into the bottom of the furnace to deliver the gas which is ignited at that point when mixed with the air admitted around said burners. Valves 18 control the supply of gas to the pipes 16 connected to the main supply-pipes 19. Gas-pipes 20 are also connected to the main supply pipes 19 at the side of the furnace, and said pipes have the inwardly projecting burners 21 which deliver gas to the side openings 22. By this arrangement of the gas-pipes the gas is distributed evenly throughout the checker-work chambers so as to give an even distribution of heat.

75 The annealing chamber 13 is closed at each end by suitable doors 23.

When my improved furnace is in use the glassware to be annealed is mounted on a suitable truck or stand and introduced into the annealing chamber 13 whereupon the doors 23 are closed and the annealing chamber sealed. The gas is admitted to the burners 17 by opening the valves 18 and combustion takes place in the checker-work chambers which will become highly heated, the products of combustion passing up through said checker-work pass by the flues 15 into the vertical flues 7 thence to the flues 8 and 9. The sliding damper 10 controls the draft in the flue 9 and by operating said damper the temperature of the furnace can be evenly and accurately controlled.

90 The construction of my improved annealing furnace is such that either the producer gas or natural gas may be employed without change of construction or rearrangement of the parts, and by the employment of the checker-work chambers, the heat is stored up and greater heating efficiency is obtained so that a maximum amount of heat is had from a minimum consumption of gas.

100 What I claim is:

1. In a furnace for annealing articles of glassware, the combination of the sides and top, an annealing chamber inclosed thereby, flues formed in the sides and top around said chamber, a series of checker-work chambers at the bottom of said furnace com-

- municating with said flues, and means for delivering air and gas to said checker-work chambers, and a stack with which said flues communicate.
5. 2. In a furnace for annealing articles of glassware, the combination of the sides and top, an annealing chamber inclosed thereby, flues formed in said sides and top around said chamber, and checker-work 10 chambers at the bottom of said furnace communicating with said flues, means for admitting gas at the front to supply the forward checker-work chambers, and means for delivering gas at the side to the remaining checker-work chambers.
15. 3. In a furnace for annealing articles of glassware, the combination of the sides and
- top, an annealing chamber formed within said sides and top, arches extending from side to side, a bottom for said annealing chamber supported on said arches, flues formed in said side walls between said arches, said flues communicating at the top, a stack communicating with said flues, a series of checker-work chambers at the bottom of said furnace between said arches, and means for supplying gaseous fuel to said checker-work chambers.
- In testimony whereof I, the said MAURICE A. SMITH, have hereunto set my hand.
- MAURICE A. SMITH.
